UNITED STATES PATENT OFFICE

166,931

CHRISTMAS BELL UNIT

Sajjan Singh Sarna, New York, N. Y.

Application February 27, 1952, Serial No. 18,678

Term of patent 3½ years

(Cl. D29—1)

To all whom it may concern:

Be it known that I, Sajjan Singh Sarna, a citizen of the United States of America, residing at New York, State of New York, have invented a new, original, and ornamental Design for a Christmas Bell Unit, of which the following is a specification, reference being had to the accompanying drawing, forming a part hereof.

Figure 1 is a front elevational view of a Christmas bell unit showing my new design;

Figure 2 is a rear elevational view thereof;

Figure 3 is a side elevational view thereof; and

Figure 4 is a top plan view thereof.

I claim:

The ornamental design for a Christmas bell unit, as shown.

SAJJAN S. SARNA.
